UNITED STATES PATENT OFFICE

123,096

DESIGN FOR A COMBINED COMB AND HAIR ORNAMENT

Siegfried Behr, Flushing, N. Y.

Application September 6, 1940, Serial No. 94,829

Term of patent 3½ years

To all whom it may concern:

Be it known that I, Siegfried Behr, a citizen of the United States, residing at Flushing, county of Queens, State of New York, have invented a new, original, and ornamental Design for a Combined Comb and Hair Ornament, of which the following is a specification, reference being had to the accompanying drawing, forming part thereof.

Fig. 1 is a front view of a combined comb and hair ornament showing my new design.

Fig. 2 is an end view thereof.

I claim:

The ornamental design for a combined comb and hair ornament, substantially as shown.

SIEGFRIED BEHR.
